APPARATUS FOR APPLYING FLANGED CLOSURES

Clifford B. Terry, Flushing, N. Y., assignor to Lily-Tulip Cup Corporation, New York, N. Y., a corporation of Delaware

Application April 28, 1941, Serial No. 396,702

3 Claims. (Cl. 226—30)

This invention relates to machines for applying caps, such as closure or cover elements, to receptacles. The invention is more especially intended for applying flanged paper caps to interfitting receptacles; and the invention has been successfully incorporated in machines for filling and packaging edibles such as ice-cream in paper containers.

Machines are well known in the art for filling containers, such as paper receptacles, wherein the containers are fed past a filling station, filled and thereafter capped; the caps or closure members being successively fed to the capping station from the magazine in which the caps are stacked. Devices have been provided for feeding cardboard disc caps or similar flangeless caps in conjunction with such machines and the like; one such device being disclosed in Henry Blann application, Serial No. 326,003, filed March 26, 1940. However, it has been found that these previously known devices are entirely unsuited for feeding flanged caps. For example with flanged caps in stack formation it is practically impossible to prevent the flange of a superimposed cap from interfering with the transverse feed of a lower cap upon which it rests. Moreover, where the flanged caps are made of relatively thin material and are subject to warpage prior to application on the supporting lip of a receptacle, such warpage increases the difficulty of feeding and applying such caps by a machine; especially where the caps are of the "snap-on" type. Such flanged "snap-on" caps, and interfitting receptacles are exemplified in James D. Reifsnnyder Patent No. 2,233,489, dated March 4, 1941.

An object of this invention is to provide a feeding mechanism for positively and accurately feeding individual caps successively from a magazine or holder in which a plurality of caps are stored; and more especially for such a device which is suited for feeding flanged paper caps of the character described.

Another object of the invention is to provide a capping mechanism suitable for individually successively feeding flanged paper caps from a magazine containing a plurality of said caps into a capping head and for holding said caps in flat position within said head, even when said caps are warped.

The invention consists in the novel features of construction, arrangement, and combination of parts embodied, by way of example, in the apparatus hereinafter described as illustrating a present preferred form of the invention, and the

invention will be more particularly pointed out in the appended claims.

Further objects and advantages of the invention will more fully appear from the following description taken in connection with the accompanying drawings which show, by way of example, the present preferred embodiment of the invention.

Referring to the accompanying drawings in which the same reference characters indicate the same parts in the various views:

Fig. 1 is a plan view of an embodiment of the invention in the form of a machine for packaging ice-cream in paper containers; certain parts relating to the ice-cream filling mechanism being omitted as forming no part of this invention and as well known to those skilled in the art.

Fig. 2 is a side elevation, partly in section, showing further details of certain parts illustrated in Fig. 1.

Fig. 3 is a detailed sectional view of the lower part of the capping head illustrated in Fig. 1 and showing a cap in position within said head.

Fig. 4 is an end view of the device illustrated in Fig. 1, as viewed from the right-hand portion of said figure, and showing certain of the parts in section.

Fig. 5 is a partial diagrammatic view in elevation showing the suction system.

Fig. 6 is a plan view partly in section, taken approximately along the plane 6—6 of Fig. 4, and illustrating the cap-feeding mechanism in position to start feeding a cap transversely toward the capping head.

Fig. 7 is a similar view showing the feeding mechanism in the position where the cap has just been fed into the capping head.

Fig. 8 is a plan view of a detail of the transverse feeding mechanism.

Fig. 9 is a vertical cross section view taken at 9—9 of Fig. 6 and showing the corresponding position of the mechanism after the cap has been fed downwardly into position to be fed transversely.

Fig. 10 is a view similar to Fig. 9 and taken at 10—10 of Fig. 7, showing the corresponding position of the mechanism for feeding the cap downwardly into position before the commencement of such downward feed.

Figs. 11 and 11a show further details in the cycle of operation of certain parts illustrated in Figs. 6, 7, 9 and 10 for inhibiting the downward feed of the caps at such time as a cap remains in the capping head.

Figs. 12, 13 and 14 are respectively plan, side-

elevation and end views showing further details of the downward feeding mechanism in the position of the cycle of operation illustrated in Fig. 9.

Figs. 15, 16 and 17 are similar views showing the comparable position of the parts illustrated in Fig. 10.

General structure

Referring more particularly to Fig. 1, the main frame of the machine comprises a pedestal or vertical frame member 1 to which is secured a table portion 2 on which the containers to be filled, such as 3, are supported. A suitable device for supplying measured quantities of ice-cream (not shown) is positioned with a downwardly extending outlet in axial alignment with the filling station designated A and suitable stops, such as 4, are provided for insuring alignment of the receptacle 3 at station A and similar stops 4' are provided for preventing the preceding receptacle from moving into capping position until the proper time; said stops being movable downwardly to permit the forward movement of the receptacle on the table 3 toward the capping head position at station B in timed relation to the capping operation. After the receptacle has been capped at station B, it is discharged at station C to a suitable shelf or conveying means (not shown). A plurality of caps are arranged in stack formation at station D from where they are individually successively fed downwardly and thence transversely to the capping head at station B, in a manner to be more particularly pointed out following.

Power is delivered to the machine from a suitable source by a belt 5 engaging a pulley 6 secured to the outer end of a drive shaft 7 suitably journalled in the frame 1, and this shaft is geared to a transverse shaft 8 (Fig. 4) by means of a pair of worm wheels 9. The shaft 8 is suitably journalled in the frame 1 and at its forward end (Fig. 4) is in driving engagement through a pair of bevelled gears 10 with one end of a shaft 11 (Fig. 2), whose other end, through a pair of bevelled gears 12, drives a shaft 13 to the end of which (Fig. 1) is secured a pulley 14 around which passes conveyor belts 15, which are preferably in the form of resilient spring belts; and these spring belts extend slightly above the top of the table 2 (Fig. 4) and serve to move the containers 3 in the manner previously described. The containers are guided in their movement along the table 2 by means of rails 16-17; and when the containers are stopped by the pins 4 or 4' the conveyor members 15 slide beneath the containers.

Positioned as an insert in the table 2 (Figs. 4 and 1) and disposed at station B, is a vertically movable table segment 18 mounted on a vertically reciprocable plunger 19 to which motion is imparted from the drive shaft 7; so that the table portion 18 is moved upwardly toward a capping head 20 which is supported for limited vertical movement in a journalled arm 21 rigidly attached to the machine frame. The table portion 18 is provided with slots 15' to receive the belts 15 as the portion 18 moves upwardly. Suitable stop pins 18' pass through the table portion 18 and are movable upwardly in timed relation to hold the receptacle in register with the head 20; said stops being movable downwardly to permit the discharge of the capped container. The capping head and movable table portion 18 are in axial alignment at station B and the relative vertical

movement between them serves to bring a cap carried in the head (Fig. 3) into interlocking engagement with a receptacle or container 3 carried on the table portion 18, in a manner to be more particularly pointed out following. Referring more particularly to Figs. 4 and 1; the cam 22 is secured to the outwardly extending end of the shaft 8 and is provided with a groove in which is seated the roller 23 pivotally mounted on the outer end of a slide bar 24 suitably journalled for reciprocation in the frame 1 and whose inner end is provided with a pin 25 which is in driving engagement in a cooperating bifurcation provided in the rear end of an arm 26 pivotally journalled about a fulcrum bolt 27 supported on the frame bracket 28 rigidly secured to the frame 1. It will therefore be seen that as the shaft 8 is rotated this rotary motion is transformed to a reciprocating motion imparted to the forward end of the arm 26 and this reciprocating motion effects two separate but related operations. (1) to withdraw respective caps from the magazine at station D and (2) to feed said caps from station D into the capping head 20. The withdrawing feed will first be described.

Withdrawal of caps from stack

Referring more particularly to Figs. 1, 2 and 4; an arm 29 is pivotally supported at its rear end by a stud 30 carried on an extension 31 rigidly secured to the frame bracket 28. The arm 29 is urged upwardly by means of a compression spring 32 (Figs. 12, 13 and 14) interposed between the lower side of the arm and the lower extremity of a C-bracket 33 carried by the support 31; the spring being centered by studs 34-35 respectively secured to the arm and bracket, and the upper limit of movement of the arm 29 being adjustably determined by means of the stop 36 which is also carried by the bracket 33. A cam spacing block 37 is rigidly secured to the underside of the arm 29 and carries spaced inwardly therefrom a cam 38, the upper surface of which is in the horizontal arcuate path of travel of a cooperating cam roller 39 which is pivotally mounted on the forward end of the arm 26, previously described. Accordingly, when the arm 26 moves in an anti-clockwise direction (as viewed from above) the cam roller 39 engages the cam 38 to move the same downwardly to thereby swing the arm 29 downwardly against the force of the compression spring 32 (Figs. 13 and 14). The free end of the arm 29 carries a tubular arm 40 rigidly secured thereto and having an upwardly extending end to which is secured a rubber suction cup 41. The other end of the tube 40 is connected by a flexible tube 42 to a suction line 43 (Fig. 5) in communication through a valve 44 with a source of suction such as a pump 45; the valve 44 being opened and closed by a link 46 connecting the valve stem to the reciprocating arm 26 and the parts being so constructed and arranged that as the sucker 41 moves into engagement with the underside of a cap such as 47 (Fig. 16) suction is exerted to cause the cap to adhere to the sucker 41 and upon downward movement of the arm 29 the cap is moved downwardly from a stack of caps designated as 48. The stack of caps 48 is held in a suitable magazine 49 (Fig. 2) providing yieldable means such as the spring fingers 50 for supporting the stack and permitting individual caps to be successively withdrawn through said fingers 50 upon the downward movement of the sucker 41.

Transverse feed of cap

Referring more particularly to Figs. 1 and 2; it will be seen that the magazine 49 is supported on the outer end of the frame bracket 28 and a slight recess is provided beneath the stack 48 for receiving a cap removed therefrom preparatory to the cap being fed transversely of the capping head. This transverse feed is effected by the pusher member 51 (Figs. 6 and 9) which is bifurcated to provide feed fingers 52 which straddle the sucker member 41 as the pusher is reciprocated back and forth by means of a slide 53 (Fig. 8) mounted in a groove in the frame portion 31 and provided with a recess 54 receiving adjustable nuts 55 on the rearwardly extended threaded end of the pusher 51. The slide 53 is pivotally connected to the reciprocating arm 26 by means of a rod link 56 and associated studs. It will therefore be seen that as the arm 26 moves in a clockwise direction motion is imparted to the pusher fingers 52, causing them to engage and feed forward the cap then in position to be thus fed. The forward ends of the pusher fingers are undercut to avoid lifting the cap. The timing of the foregoing mechanism is such that as the pusher 51 (Figs. 9 and 10) is feeding the cap 47 toward the capping head 20, and after the said cap has been fed beyond the position of the sucker 41, the sucker commences its upward movement to engage the lowermost cap then remaining in the stack (Fig. 10) and as the pusher 51 moves rearwardly from the position shown in Fig. 10 the sucker 41 is moved downwardly to place a cap in the position illustrated in Fig. 9 ready to be fed forward on the succeeding feed stroke of the pusher 51. It is noted at this point that the return or idle stroke of the sucker 41 into engagement with the lowermost cap of the stack is brought about by the compression spring 32 (Fig. 12) so that slight deviations in the horizontal plane of the bottommost cap of the stack do not prevent the suction engagement between the sucker and the cap; and likewise irregularities in the position of the top of the cap (such as result from warpage of the cap) will not detrimentally affect the proper engagement of the cap by the sucker. Likewise, these slight variations will not affect the feeding stroke of the sucker 41 since the cam plate arrangement permits these variations and produces a final lower position of the sucker below the horizontal position at which the cap 47 comes to rest at the end of its down stroke.

As the cap 47 is fed forward it passes into and through an opening or gate 57 provided in the capping head 20 and in communication with the inner chamber or cap recess 58; so that the cap is positioned within said chamber 58. Oppositely disposed pins 59—60 (Figs. 6 and 3) are supported by springs such as 61 so that the inner ends of the pins pass through the head and into the chamber 58 in position to engage the cap. In the present embodiment these pins are adapted to engage the external recess in the cap flange (Fig. 3) and serve a dual purpose. (1) They are offset from the diameter of the cap and therefore serve to center the cap in the chamber 58 and (2) they serve to prevent the cap from falling out of the head under the conditions to be hereinafter described. As the cap is fed into the chamber 58 it comes under the influence of a rather strong suction exerted within the chamber through an axial bore 62 which is connected to a suitable source of vacuum in the manner illustrated in

Fig. 5. In the present embodiment this vacuum is of the order of 22 inches of mercury and is sufficient to cause the cap to lie flatly against the upper face of the chamber 58, thereby causing the cap to be accurately positioned within the head even though the cap be warped. This vacuum line performs the additional function of holding the cap snugly up against the lower face of the head 20 as it is being fed into position within the head and thereby prevents the forward edge of the cap from dropping down and assures the engagement of the cap by the fingers 59—60. In order to permit the cap to be discharged under the weight of the filled receptacle to which it has been applied, the suction is interrupted by means of a suitable valve 63 (Fig. 5) controlled by the valve arm 64 whose free end carries a cam roller 65 engaging a cam 66 driven by the shaft 8 (Fig. 2), and provision is made to vent the line upon the raising of the head 20, so as to immediately break the suction line and relieve the head from suction. Venting is accomplished by a relief hole 20' (Fig. 4) provided in the stem of head 20 and extending radially from the bore 62 outwardly through the stem wall in vertical spaced alignment with a cooperating hole 21' through the journal bracket 21. Upon upward movement of the head 20 the holes 20'—21' come into register, thereby immediately breaking the vacuum. If for any reason the receptacle is not supplied to a cap positioned in the head 20, then the spring fingers 59—60 exert sufficient force on the cap to prevent it from falling out; but these fingers do not exert a sufficient force to hold a cap against the weight of a filled receptacle to which the cap has been applied.

Inhibiting cap feed

The following provision is utilized to prevent the cap-feeding mechanism from feeding a cap to the capping head when a previously fed cap still remains in said head. A cap supporting pair of spaced-apart cam plates 67 (Figs. 6 and 9) are attached together adjacent their forward ends by means of a cross pin 68 and are seated in cooperating slots 69 formed in the frame portion 31. These plates are provided with cam portions 70 engageable with cooperating cam pins 71 carried by the frame portion 31 and extending into the slot 69 so that as the cam plates are moved forward they are lifted to the point of dwell on the cam portions 70 and are held in this position until displaced; the cam plates 67 being given this forward motion upon the forward stroke of the pusher slide 53, whose forward end engages the cross pin 68 (Fig. 7). In the raised position these connected plates 67 provide a positive support and inhibit the feeding of caps transversely from the stack (Fig. 11) because when the support is in its upper position the cap is prevented from any transverse displacement from the stack by the wall of the magazine 49. As the receptacle 3 is moved upwardly into engagement with the cap carried in the head 20, the limited movement upwardly of the head 20 causes the bevel faces 72 (Figs. 11 and 6) to engage the corresponding bevel noses on the plates 67 which raises the plates and disengages them from the pins 71 against which the cam portions 70 ride to return the plates 67 to their rearwardly and downwardly inactive positions, as illustrated in Fig. 11a, so that the next succeeding cap may be fed to the capping head. On the other hand, if no receptacle comes into engagement with the head 20 so as to cause

it to be lifted, the plates 67 remain in the position indicated in Fig. 11.

Operation

Referring to Fig. 1; after the container 3 has been filled at station A the stop pins 4 move downwardly and the spring belts 15 convey the receptacle toward station B; but before it reaches station B the succeeding container has arrived at station A and the pins 4 and 4' again move upwardly, the pins 4' stopping the movement of the filled container until the pins 4' are next moved downwardly to permit the container to be fed to station B where it comes into engagement with the pins 18' (Fig. 4) which serve to hold it in axial alignment with the capping head 20. During this movement of the container to the capping station the cap has been finally inserted into the capping head 20 in the manner to be more particularly described following.

Commencing with the sucker 41 in the position indicated in Fig. 10; the sucker has come into operative engagement with the cap 47 and as the arm 26 rotates in an anti-clockwise direction the roller 39 engages the cam 38 and positively moves the sucker downwardly (Fig. 5), during which time the valve 44 is open. Upon continued downward movement of the sucker 41 (Figs. 12 and 13) the cap is seated on the cam plates 67 and the sucker continues to move downwardly withdrawing from engagement with the cap. Preferably, the suction to the sucker 41 is interrupted by the closing of the valve 44 immediately after the cap has been seated on its support. At the time that the cap 47 is seated on its support the pusher bar fingers 52 are spaced somewhat rearwardly of the edge of the cap and after the cap has been seated on its support the fingers 52 move forward into feeding engagement as shown in Fig. 13. The arm 26 is now moving in a clockwise direction and the fingers push the cap from the position indicated in Fig. 9 through the gate 57 into the chamber 59, as shown in Fig. 10 (see also Fig. 3); suction through the bore 62 then being exerted to seat the cap in level alignment within the capping head 20. During the forward movement of the transverse feeding fingers 52 the sucker 41 is being moved upwardly under the influence of the compression spring 32, as the roller 39 (Figs. 13-17) passes off the cam 38, and the sucker passes between the bifurcations 52, thereby permitting the spring 32 to resiliently but firmly engage the sucker 41 with the cap 47—the upward limit of movement being determined by a suitable adjustment of the stop 36.

During the active or feeding movement of the fingers 52 the pusher slide 53 (see also Fig. 7) has moved the plates 67 forward to the position indicated in Figs. 10 and 11. Upon the commencement of the idle or return stroke of the fingers 52 the table portion 18 (Fig. 4) is moved upwardly so as to bring the upper lip of the receptacle 3 into interfitting engagement with the cap 47 then positioned in the capping head 20. This causes the head 20 to be lifted and the bevel faces 72 engage the cam noses of the plates 67 to thereby lift the plates and return them to the position illustrated in full lines in Fig. 11a; thereby permitting the succeeding cap in the magazine 49 to be fed transversely. At the time that the head 20 has been thus lifted the suction through the bore 62 has been shut off, and the head immediately and fully vented through the holes 20'-21', as previously de-

scribed; and the weight of the filled and capped container 3 forces the spring held fingers 59—60 (Fig. 3) outwardly, permitting the filled container to be deposited upon the spring belts 15 (Fig. 4). At this time the table portion 18 has been lowered and the pins 18' have been moved below the conveyor springs 15, thus permitting the filled container to be discharged (Fig. 1) over the pulley 14.

From the foregoing it will be seen that if no container is fed to the capping station the capping head is not raised and thereafter the plates 67 (Figs. 11 and 11a) remain in the upper or active position and thereby inhibit the feeding of successive caps until the capping head 20 has been raised. It will be understood that the suction supplied to the sucker 41 is not sufficiently great to damage either the sucker or the cap and that the positive downward movement of the sucker 41 by the cam 38 (Figs. 12 and 13) is sufficient to disengage the sucker from the cap, whether the cap be supported on the cam plates 67 in raised position, as shown in Fig. 11, or in lowered position, as shown in Fig. 9. It will be understood that as long as the cam plates are in raised position (Fig. 11) the sucker merely engages and disengages the same cap 47; whereas as long as the head 20 is successively raised during each cycle of operation the sucker engages the respectively successive caps to withdraw them from the stack and into the transverse feeding position for successive movement into the feeding head 20.

Although the invention is especially intended for handling flanged closure caps of the character described, and has proven to be ideally suited for this purpose; it is also adapted for handling disc caps and the like.

Having thus described my invention with particularity with reference to its presently preferred form, it will be obvious to those skilled in the art, after understanding my invention, that other changes and modifications may be made therein without departing from the spirit and scope of my invention, and I aim in the appended claims to cover such changes and modifications as are within the scope of the invention.

What is claimed is:

1. In a capping device for applying circular caps to receptacles, the combination of a capping head provided with a face against which said cap is to be seated and a downwardly extending flange for limiting the forward movement of a cap fed into said head, resilient fingers disposed below said face and extending inwardly from respectively opposite peripheral sides of said head relative to the direction of said movement for supporting a cap on said head, means for feeding a cap forwardly against said flange and between said fingers into position on said head, suction means for urging said cap vertically against said face, said resilient fingers being positioned rearwardly from the position on said head corresponding to the diameter of said cap in order to securely center the cap laterally on the head, said suction means being provided with a mouth of a relatively small area disposed contiguous the level at which the cap is fed forwardly into the head to insure a vacuum seal upon portions of the cap surface as the cap is fed forward, said feeding means and resilient fingers and suction means being so constructed and arranged that the suction means supports the forward portion of said cap during the forward feeding movement thereof into position on said head and assures

the supporting engagement of said cap by said resilient fingers.

2. In a capping device for applying circular caps to receptacles, the combination of a capping head provided with a face against which said cap is to be seated and a downwardly extending flange for limiting the forward movement of a cap fed into said head, resilient fingers disposed below said face and extending inwardly from respectively opposite peripheral sides of said head relative to the direction of said movement for supporting the cap on said head, means for feeding a cap forwardly against said flange and between said fingers into position on said head, said resilient fingers being positioned rearwardly from the position on said head corresponding to the diameter of said cap in order to securely center the cap on the head, said feeding means and resilient fingers being so constructed and arranged to assure the supporting engagement of said cap by said resilient fingers.

3. In a capping device for applying circular caps to receptacles, the combination of a capping head having a face against which said cap is to be seated and a downwardly extending flange for limiting the forward movement of said cap as it is fed into said head, said head being provided with suction means centrally located therein and terminating adjacent the face of said head, means for feeding a cap forwardly against said flange and contiguous the face of said head within the zone of action of said suction means, said suction means being confined to a relatively small area of said face to insure a vacuum seal upon a relatively small area of the cap surface as said cap is fed forward, said feeding means and suction means being so constructed and arranged that the said suction means supports the forward portion of said cap during the forward feeding movement thereof into position on said head.

CLIFFORD B. TERRY.
